W. H. ROSE

WINDOW VENTILATOR

Filed Nov. 18, 1926

Fig. 1.

INVENTOR
William H. Rose
BY
Frank Freeman
his ATTORNEY

UNITED STATES PATENT OFFICE.

WILLIAM H. ROSE, OF JERSEY CITY, NEW JERSEY.

WINDOW VENTILATOR.

Application filed November 18, 1926. Serial No. 149,038.

The device of my invention relates to ventilators and refers particularly to ventilating deflectors for window use.

One of the objects of my invention is a 5 ventilator in which the deflector element is readily attached to, and removed from the supporting side pieces.

Another object of my invention is a ventilator free from noise and rattle incident to 10 air impact.

Another object of my invention is a ventilator made of inexpensive material.

Another object of my invention is a 15 knock-down ventilator which can be easily assembled and easily set up.

The above and other valuable features of the device of my invention will be evident upon a consideration of the attached drawings and my explanation thereof.

20 In the accompanying drawings illustrating modified forms of the device of my invention, similar parts are designated by similar numerals.

Figure 1 is a front view of the device of 25 my invention in window frame placement.

Figure 2 is a cross-section through the line 2—2 of Figure 1.

Figure 3 is an enlarged cross-section 30 through the line 3—3 of Figure 1.

Figure 4 is a perspective view of the end support of my device.

Figure 5 is a fragmentary side view of 35 the deflector.

Figure 6 is a fragmentary vertical cross-section of a modified form of deflector.

The particular form of the device of my invention shown in Figures 1 to 5 inclusive comprises a deflector 10 made of corrugated cardboard having a protective edging of 40 paper, or textile material, 11 attached to and covering its upper edge.

My device, as illustrated, has two end supports each having a window casement element 12 and an angularly positioned deflector support 13, each deflector support 13 having a plurality of bent over cut-out fasteners 14, 14. Each casing element 12 has a plurality of openings 15, 15 for purposes described later.

50 It is evident from the above that the device of my invention comprises a cardboard deflector and two metallic end supports. The end supports may be in the form of a flat blank, scored to allow of the angular 55 positioning of the elements 12 and 13 with

respect to each other, and that the fasteners 14, 14 may also be in unbent position. My knock-down device, therefore, occupies but little space and has advantageous shipping and storing properties.

60 The formation of the operative device from the blank and its erection and attachment is as follows:—

The deflector support 13 of each end support is bent at right angles to the casement element 12 and each fastener 14 is bent at right angles to its deflector support 13. The two end supports are then attached to the two window casements 16, 16 by means of 70 nails, or screws, passed through the openings 15, 15. The fasteners 14, 14 are then passed through corresponding openings 17, 17 in the deflector 10 and bent down to about 75 upon the further face of the deflector, as shown particularly in Figure 3.

75 The deflector 10 may be attached to the end supports 12, 12 before the latter is attached to the casement if desired.

The modified form of my device shown 80 in Figure 6 is similar to that described, except that a metallic rod 18 is positioned upon and held upon the upper edge of the deflector 10 in order to increase its rigidity.

In order to remove the deflector 10, the 85 fasteners 14, 14 are straightened and the deflector withdrawn.

The deflector 10 may be painted and water-proofed if desired.

It will thus be seen that my device is 90 economic in cost, possesses valuable packing and shipping properties, is readily assembled and readily attached, that the deflector may be readily removed and that, because of the fact that there is no metal-to-metal contact, it is free from rattle and noise 95 due to irregular wind impacts.

I do not limit myself to the particular size, shape, number, arrangement or material of parts, as these are simply given as a means for clearly describing my invention.

100 What I claim is:—

1. In a window ventilator, in combination; two end supports, each having a casement member, an angularly positioned deflector support and a plurality of extended 105 fasteners from the deflector support; and a deflector having openings therein through which the fasteners may be inserted and bent over, attaching the deflector to the deflector supports.

2

2. In a non-rattling window ventilator, in combination; two metallic end supports, each having a casement member, an angularly positioned cardboard deflector support and a plurality of extended fasteners from the deflector support; and a deflector having openings therein through which the fasteners may be inserted and bent over, attaching the deflector to the deflector supports.

3. In a window ventilator, in combination; two end supports, each having a casement member, an angularly positioned deflector support and a plurality of extended fasteners from the deflector support; a deflector having openings therein through which the fasteners may be inserted and bent over, attaching the deflector to the deflector

supports and a stiffening member carried by the deflector.

20

4. In a non-rattling window ventilator, in combination; two metallic end supports, each having a casement member, an angularly positioned cardboard deflector support and a plurality of extended fasteners from the deflector support; a deflector having openings therein through which the fasteners may be inserted and bent over, attaching the deflector to the deflector supports and a stiffening member carried by the deflector.

25

Signed at New York city in the county of New York and State of New York this 11th day of November, 1926.

30

WILLIAM H. ROSE.
